UNITED STATES PATENT OFFICE.

THOMAS H. DUNHAM, OF BOSTON, MASSACHUSETTS.

IMPROVEMENT IN MACHINERY FOR REDUCING ROPE TO FIBER.

Specification forming part of Letters Patent No. 36,080, dated August 5, 1862.

To all whom it may concern:

Be it known that I, THOMAS H. DUNHAM, of Boston, in the county of Suffolk and State of Massachusetts, have invented an Improved Rope-Picking Machine, of which the following is a full, clear, and exact description, reference being had to the accompanying drawings, making part of this specification, in which—

Figure 1 is a perspective view of the machine; Fig. 2, a longitudinal vertical section through the same.

I am aware that machines have been constructed for picking cotton, to loosen up and separate its fibers; also machines for tearing up woolen rags, cloth, old bagging, &c.; also machines for picking oakum. In these latter the tarred rope was fed in to the picker-cylinder from between feed-rolls, which compressed it firmly, and not only prevented the rope from being dragged in too rapidly by the picker-cylinder, but also prevented the fibers from drawing out from the rope beyond the point of contact of the feed-rolls, the result being that the picker-cylinder, in tearing off the fibers from the end of the rope, broke them up into short lengths. To this there was no objection in an oakum-machine. In my present invention, however, I design to produce a machine for picking untarred rope, and separating its fibers, so that they may be again spun; and my invention consists in the combination of a picker-cylinder and such a feed as will not compress the rope so hard at any particular point as to prevent the fibers from being drawn out from it by the picker-cylinder, and yet will hold it so that the mass of rope cannot be drawn in and wound round the picker-cylinder, and this I attain by the employment of a serrated or saw-toothed feed-roll operating in combination with a curved bed which keeps the rope in contact with a considerable portion of the periphery of the feed-roll.

That others skilled in the art may understand and use my invention, I will proceed to describe the manner in which I have carried out the same.

In the said drawings, A is the frame of the machine in suitable bearings, on which is supported the shaft *a* of the picker-cylinder B. This cylinder has at intervals around its periphery lags *b*, furnished with teeth *c*, and is driven rapidly by any suitable power in the direction of the arrow 5. A belt, *f*, from a

pulley on the shaft *a* drives a shaft, *g*, which carries on its end a pinion, C, which, through an intermediate gear, D, drives a wheel, E, on a shaft, *h*, in the direction of the arrow 6. This shaft *h*, which runs in bearings *i*, carries the feed-roll F, the surface of which is serrated or toothed, the teeth *m* being formed like the teeth of a saw, pointing in a direction opposite to that in which the roll revolves.

Immediately beneath the roll F, and extending across the machine, is a metal bed, G, the upper face, *n*, of which is curved concentric with the roll, while the edge *o* of it rises above a horizontal plane touching the lower side of the roll, and is set at a proper distance from the path of the teeth of the picker-cylinder B. A feed-table, H, on which to place the stock, extends back from the rear edge of the bed G, and is supported on top of the frame of the machine. The space between the roll F and bed G is made to suit the size of rope to be operated on, which is selected of a nearly uniform size. The stock to be operated on is spread on the table H, (as represented in blue,) and is carried by the feed-roll F forward to the cylinder B, the teeth of which drag it over the edge *o* of the bed G, tear it up, and separate its fibers, the teeth *m* of the roll F preventing the rope from being dragged through between the roll F and the bed G any faster than the revolutions of the roll permit, while the curved bed G holds the rope in contact with so great a number of the teeth of the roll F that the rope does not require to be nipped or compressed at any part of its length so hard as to prevent the fibers from being drawn out by the picker-cylinder. It will be observed by an inspection of the gearing that the roll F is driven quite slowly in comparison with the cylinder B. A cap or hood, I, covers the cylinder B, and prevents the escape of the fibers which have been operated on by this cylinder, except at the opening K at the rear of the machine, where they are discharged.

What I claim as my invention, and desire to secure by Letters Patent, is—

The picker-cylinder B, in combination with the toothed feed-roll F, and curved bed G, operating substantially as described, for the purpose specified.

THOMAS H. DUNHAM.
